JAW PROP OR THE LIKE

Michael Drozenigg, Denver, Colo.

Application August 7, 1952, Serial No. 20,943

Term of patent 7 years

(Cl. D83—1)

To all whom it may concern:

Be it known that I, Michael Drozenigg, a citizen of the Republic of West Germany, residing at Denver, State of Colorado, have invented a new, original, and ornamental Design for a Jaw Prop or the like, of which the following is a specification, reference being had to the accompanying drawing, forming a part hereof, in which:

Fig. 1 is a top plan view of a jaw prop or the like embodying my new design;

Fig. 2 is a side elevational view taken from the left of Fig. 1;

Fig. 3 is an end view looking from below in Fig. 1; and

Fig. 4 is a section taken on line 4—4 of Fig. 1.

I claim:

The ornamental design for a jaw prop or the like, as shown.

MICHAEL DROZENIGG.
